UNITED STATES PATENT OFFICE.

JOSEPH W. DYE, OF LONG BEACH, CALIFORNIA.

HANDLE.

Application filed January 11, 1923. Serial No. 612,116.

To all whom it may concern:

Be it known that I, JOSEPH W. DYE, a citizen of the United States, residing at Long Beach, in the county of Los Angeles and State of California, have invented a new and useful Handle, of which the following is a specification.

This invention aims to provide a simple means whereby a new handle may be mounted quickly, without the use of tools, upon the bail of a cooking pot or other utensil.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention; Figure 2 is a longitudinal section; Figure 3 is a section on the line 3—3 of Figure 1; Figure 4 is a section on the line 4—4 of Figure 1; Figure 5 is a diagrammatic cross section illustrating the operation of the device.

The handle forming the subject matter of this application comprises two sections 1, each of approximately circular cross section, the sections being made of wood or any other suitable material. Cooperating longitudinal grooves 2 in the inner or meeting surfaces 5 of the sections 1 define a bore 3 in the handle. Adjacent to its ends, the handle has circumferential seats 4. The sections 1 are cut away at their ends, and at their inner or meeting surfaces 5, to form entering notches 6. Prehensile spring binders 7, preferably made of metal, are located in the grooves 2 and hold the sections 1 together, the ends of each binder being spaced, as indicated at 8.

When it is desired to mount the handle

on a bail 9, the binders 7 are turned until they occupy the position of the binder at the right hand of Figure 1, that is, until the space 8 between the ends of each binder is located at the place where the handle is divided longitudinally. Then, the bail 9 is passed into the bore defined by the grooves 2, the bail passing through the space 8 in each binder, and between the inner surfaces 5 of the sections 1, an observation which will be understood readily when Figure 5 is noted. Owing to the fact that the notches 6 are provided, the bail 9 may be started readily into place between the sections 1 of the handle. After the bail 9 is in place in the bore 3, the binders 7 may be turned slightly, until both of them assume the position occupied by the binder at the left hand end of Figure 4. It is to be observed that in the mounting of the handle of the bail, it is not necessary to remove the spring binders 7 from the handle, the binders simply being turned until both of them occupy the position indicated at the right hand end of Figure 1.

What is claimed is:—

1. A handle comprising laterally separable sections having abutting inner surfaces, and prehensile spring binders surrounding the sections, the sections being provided with superficial means for holding the binders on the sections, the binders having free ends and being rotatable in said means and on the handle, to space the free ends of the binders from the inner surfaces of the sections, circumferentially of the handle.

2. A handle comprising laterally separable sections having cooperating inner surfaces, the sections being cut away at one end to form entering notches coacting with the inner surfaces of the sections; and prehensile spring binders surrounding the sections and having free ends.

In testimony that I claim the foregoing as my own, I have hereto affixed my signature in the presence of two witnesses.

JOSEPH W. DYE.
